PROCESSING TANK

Carter J. Hughey, Rochester, N. Y., assignor, by
mesne assignments, to Eastman Kodak Com-
pany, Jersey City, N. J., a corporation of New
Jersey

Application November 6, 1935, Serial No. 48,527

4 Claims.

(Cl. 95—90)

This invention relates to photography and particularly to an improved cover for a processing tank which is adapted to close the tank against the admission of light and provide for the rapid introduction of the processing liquid into the tank.

In a processing tank of this type, some provision must be made for the escape of the air from the tank as it is displaced by the entering liquid, as well as providing an entrance for the air to displace the liquid as it is emptied from the tank. If only one passage is provided for the simultaneous passage of air and liquid out of and into the tank, it means that the filling or emptying of the tank is going to be retarded, because of the two passing in opposite directions at the same time. Therefore, one object of my invention is to provide a light-tight cover for a tank of this type wherein separate passages are provided for the passage of air and a liquid so that the tank can be rapidly emptied or filled. Another object is to provide a cover in which the air vent and the liquid duct are suitably positioned adjacent to each other so that they can be covered or uncovered by a simple cap.

My invention consists of a cover in which there is a liquid duct for introducing a liquid into the tank, and an air vent adjacent to the liquid duct through which the displaced air passes from said tank. A baffle plate is fastened to and spaced from the under side of the cover by a plurality of partitions which are suitably positioned relative to one another to form a pair of separate labyrinthian passages for the air and liquid entering or leaving the tank. The baffle is smaller in diameter than the tank so that the separate labyrinthian passages connect the air vent and the liquid duct with the interior of the tank in such a way that the processing liquid can be introduced into said tank without hindering the escape of the displaced air through the air vent. After the tank is filled with the processing liquid, the liquid duct and the air vent are closed by a single cap so that the tank can be inverted without losing the liquid.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing in which,

Figure 1 is a vertical cross-section of my cover positioned on a tank, and,

Figure 2 is a top plan view of the baffle showing the separate labyrinthian passages; the cooperating portions of the can and cover being shown in dotted lines for the sake of clearness.

Like reference characters refer to corresponding parts throughout the drawing.

In Figure 1, showing the preferred embodiment of my invention, reference number 1 indicates a tank having a reel 2, on which photographic material to be processed is wound, suitably positioned therein in any well-known manner. The tank 1 is closed against the admission of light by the cover 3 which is held in place by a close frictional fit between the down turned portions 4 of the cover and the walls of the tank 1 as shown. The cover 3 can be placed on the tank in any suitable manner, i. e., by screw-threaded engagement, without deviating from the spirit of my invention. A mouth or liquid duct 5, having vertical wall 6, is encircled by a raised U-shaped ring 7, between the walls of which there is a channel 8 for purposes described later in the specification.

Referring now to Figure 2, the baffle 9 is shown having a plurality of concentric and radial partitions forming a pair of separate labyrinthian passages for guiding the processing liquid into the tank and the displaced air out of the tank. The passage taken by entering liquid is shown by dotted directional arrows, while the passage for the displaced air is shown by dot and dash directional arrows. The baffle 9 is fixed to and spaced from the under side of the cover 3 by permanently seating the partitions 10 and 11 thereon in suitable recesses in the cover 3 so that liquid and light-tight joints are formed between the two at these points of junction. This means of fastening the baffle 9 on the cover forms a series of enclosed labyrinthian passages through which the fluids may pass to and from the interior of the tank, but through which no light can enter the tank. The partitions 12 are longer than the partitions 10 and 11, as shown in Figure 1, so that they extend into the channel 8 between the walls of the U-shaped ring 7 and make a tight telescopic fit with the vertical wall 6 of the liquid duct 5 thereby forming a tube with said wall through which the processing liquid is introduced to the central portion of the baffle which is surrounded by the partitions 12. After the processing liquid enters the liquid duct 5, it passes through the three openings 13 between the partitions 12, as shown by the dotted arrows of Figure 2, and on through

the labyrinthian passages to the openings 14 where it enters the tank 1. The displaced air leaves tank through the opening 15, passes through its labyrinthian passage, as shown by the 5 dot and dash arrows, and finally is expelled from the tank through an air vent 16 in the cover 3. Referring to Figure 2, it can be seen that the passage for the air is separated from the liquid passage by means of the radial partitions 17 10 and 18 in conjunction with the 180 degree segment of partitions 12. Although I have the partitions arranged on the baffle in a given pattern for the purpose of illustration, it is to be understood that the relative positions and number of 15 these partitions could be altered without deviating from the spirit of my invention as long as the passages for the air and liquid are maintained separate from one another.

After the tank 1 has been filled with liquid, 20 the liquid duct 5 and the air vent 16 are covered by a cap 19 so that the tank can be inverted without losing any of the processing liquid therein. This cap 19 is made of a light gauge metal and is adapted to be held in place by virtue of 25 the spring tension of its material of construction which acts to tightly grip the tapered walls of the raised U-shaped ring 7 surrounding the liquid duct 5.

The baffle 9 is arcuate in shape so that the 30 bottoms of the liquid passages have a decided slope toward the tank for the purpose of speeding up the entrance of the liquid into said tank. The tank is rapidly emptied by removing the cap 19 and tilting the tank so that the liquid 35 leaves the tank through the same passages through which it entered, and at the same time, the air replacing the liquid enters the tank through the air vent 16 and its associated passage.

40 It is to be understood that the form of my invention, herewith shown and described, is to be taken as a preferred example of the same, and that various changes relative to material, size, shape, and arrangement of parts may be resorted to without departing from the spirit of 45 the invention or the scope of the subjoined claims.

Having thus described my invention, what I claim is new and desire to secure by Letters Patent of the United States is:

50 1. A photographic processing tank comprising a tank, a cover for the tank including a pair of spaced plates separated by a plurality of partitions forming separate labyrinthian passages providing access to the interior of the tank, one 55 of said plates being annular in shape and includ-

ing a tubular flanged opening, said tubular flanged opening comprising two concentrically arranged walls connected at the top and perforated to form an air vent, said tubular opening and air vent leading to separate labyrinthian 5 passages, and a cap adapted to cover both the tubular opening and the air vent simultaneously.

2. A photographic processing tank comprising a cylindrical tank, a cover for said tank including a tubular flanged opening, said tubular flanged opening comprising two concentrically arranged walls connected at the top and perforated to form an air vent, a baffle plate fixed to and spaced from said cover by a plurality of partitions, said partitions adapted to form separate labyrinthian 10 passages, certain of said passages connecting the interior of the tank with the air vent, the other passages connecting said tubular opening with the interior of the tank, and a cap adapted to cover both the tubular opening and the air vent simultaneously. 15

3. In a photographic processing tank the combination with a tank, a cover for said tank including a tubular flanged opening, said tubular flanged opening comprising two concentrically 20 arranged walls connected at the top and perforated to form an air vent, of a baffle plate of lesser radius than the tank fixed to and spaced from said cover by a plurality of partitions adapted to form separate labyrinthian 25 passages, each of said passages having an opening to the edge of the baffle plate, certain of said labyrinthian 30 passages leading from the tubular opening while the others lead to the air vent, and a cap adapted to cover the tubular opening and the air vent 35 simultaneously.

4. A photographic processing tank comprising a tank, a cover for the tank including a pair of spaced plates separated by a plurality of partitions forming separate labyrinthian 40 passages adapted to give access to the interior of the tank, one of said plates being annular in shape and including a tubular flanged opening for the introduction of liquid into said tank, said tubular flanged opening comprising two concentrically 45 arranged walls connected at the top and perforated to form an air vent, said tubular opening and said air vent leading to separate labyrinthian 50 passages, the second of said spaced plates adapted to bow downwardly from its center to speed up the flow of liquid through the labyrinthian 55 passages thereon, and a cap adapted to cover both the tubular opening and the air vent simultaneously.

CARTER J. HUGHEY.
